CLAIM

The ornamental design for coffin furniture, as shown and described.

DESCRIPTION

FIG. 1 is a perspective view of the coffin furniture showing my new design;

FIG. 2 is a front view thereof;

FIG. 3 is a rear view thereof;

FIG. 4 is a top view thereof;

FIG. 5 is a bottom view thereof; and,

FIG. 6 is a right side view thereof; the left side being a mirror image thereof.
